CLAIM

The ornamental design for an adhesive dispenser/applicator device, as shown and described.

DESCRIPTION

FIG. 1 is a front/top perspective view of an adhesive dispenser/applicator device showing our design, the broken line showing of the hole defines the bounds of the claimed design but does not form part of the claimed design;

FIG. 2 is a left side elevational view thereof; the right side is a mirror image;

FIG. 3 is a top plan view thereof;

FIG. 4 is a bottom plan view thereof;

FIG. 5 is a front end view thereof; and,

FIG. 6 is a rear end view.
